ATHLETIC SHOE

Gilbert Ford, Lynnfield, Mass., assignor to Eltra Corporation, Wilmington, Mass.

Filed Oct. 3, 1974, Ser. No. 511,576

Term of patent 14 years

Int. Cl. D2—04

U.S. Cl. D2—309

FIG. 1

FIG. 3

FIG. 2

FIG. 4

FIG. 5

FIG. 6

FIG. 1 is a front elevational view of an athletic shoe showing my new design;

FIG. 2 is a side elevational view thereof;

FIG. 3 is a rear elevational view;

FIG. 4 is a side elevational view of the side opposite that shown in FIG. 3;

FIG. 5 is a top plan view; and

FIG. 6 is a bottom plan view.

The characteristic feature of my new design resides in the combination of a star and forwardly pointed chevron motif used on the side of an athletic shoe with the star adjacent and behind the V portion of the chevron and with the chevron extending generally from the top of the shoe upper to the lower edge of the shoe upper.

I claim:

The ornamental design for an athletic shoe, as shown and described.
